ELECTROLYTIC CONDENSER

David Jacobs, New York, N. Y., assignor to
 Aerovox Corporation, Brooklyn, N. Y., a corpora-
 tion of New York

Application May 17, 1937, Serial No. 143,001

6 Claims. (Cl. 175—315)

My present invention relates to electrolytic condensers, more particularly to those of the so-called "wet" type.

An object of the invention is to afford a secure 5 insulating mount in the can for the anode which shall constitute a liquid tight seal to prevent leakage of electrolyte.

Another object is to provide a mount of the above type of simple and inexpensive construction which may be readily introduced without the 10 need for spinning, rolling or compressing operations.

In the accompanying drawing in which is 15 shown one of various possible embodiments of the several features of the invention.

Fig. 1 is a fragmentary view partly in section of one embodiment of the invention,

Figs. 2 and 3 are fragmentary sectional views 20 showing successive stages in the assembly of the device, and

Fig. 4 is a perspective view, showing the assembly of riser and plug.

The general construction of the condenser may 25 be entirely conventional, including a metal container 10 having a neck 11 which may desirably have screw threads to serve for mounting upon a chassis (not shown) with the aid of a nut (not shown). A riser 12 of conventional construction is mounted in insulating relation with respect to 30 the neck 11 and has affixed thereto an anode (not shown), spaced from the can which serves as a cathode, the can being filled with suitable electrolyte liquid and at its upper end having a conventional closure affixed thereto with any suitable 35 form of vent. The general construction is but briefly and sketchily described because it is quite conventional.

The present invention is concerned entirely 40 with the construction of the liquid tight closure and riser mounting means at the lower end of the device.

According to the invention the neck of the can which is preferably integral with the can structure is extruded to present a thickened wall 13 45 capable of resisting high normal pressure without distortion. It is preferably provided with a bore that is slightly tapered to present a smaller diameter at its lower or outer end than at its upper or inner end. In a practical application the taper may be about $\frac{1}{16}$ " per inch length of the neck.

The riser is illustratively of a length of wire generally $\frac{1}{8}$ " in diameter, flattened at its upper end 14 for rivet connection as at 15 to the anode member 16. The lower unflattened portion of

the wire is introduced into a corresponding axial bore 17 of a flexible rubber plug 18 which has a taper corresponding to that of the inner wall of the neck 11 and the plug is of length considerably greater than that of said neck.

The riser wire being introduced into the plug, that assembly is introduced through the upper end of the can so that the plug will readily become seated as best shown in Fig. 2 in the neck, with the lower reduced end of the plug protruding below and the upper large end of the plug protruding above the neck. Thereupon the protruding end of the rubber plug is grasped by a suitable gripping tool and pulled downward to the position shown in Fig. 3. In that operation, 15 preferably a suitable marking on the plug, or if desired, a suitable stop in the container aids in determining that the plug has been pulled out far enough. In this operation as is immediately apparent, the rubber plug is subjected to relatively 20 tremendous wedging pressure, securely to grip the riser wire and to be compressed at its outer periphery by the entire inner area of the neck. In that position as shown, the upper or larger end of the plug protrudes but slightly above the 25 neck and since it has not been subjected to compression by the neck, flares materially in a radial direction into the can while the lower reduced end, which is relieved of the pressure exerted by the neck expands outwardly therebeyond as 30 shown at 19.

The excess length of protruding plug may then 35 be readily cut off slightly below the bottom of the neck and the usual terminal lug 20 may be applied to the protruding riser end and rest against the protruding plug end.

By the construction set forth it will be seen that a most reliable liquid tight seal is afforded by which the possibility of leakage of electrolyte from the can is substantially precluded. The 40 rubber plug is affixed with respect to the can and the rod under pressure and with effectiveness at least as great as that accomplished by the most approved cork closures applied in bottling works. Moreover, the protruding ledges 19 and 22 respectively above and below the neck 11 afford affirmative stops retaining the plug against longitudinal displacement in addition to the effectiveness of the friction hold thereof with respect to the riser and with respect to the neck.

While as set forth it is preferred to form the can neck of such thickness as not to be subject to appreciable distortion under pressure, it will be understood that the invention as defined by 55

the broader claims could be applied with a neck of somewhat weaker or thinner metal.

While the tapered bore and tapered plug construction set forth have the advantage of a more effective wedge binding effect, it will also be understood that results useful within the scope of the invention as more broadly defined could be accomplished with the use of a plug, the neck sealing portion of which is cylindrical with a neck of corresponding bore, the plug being reduced at its lower end for facility in gripping the same by means of the pulling tool to cause seating thereof.

It is seen that the present construction involves only a single unitary flexible rubber plug element to effect mount of the riser and the seal with respect to the can neck. The compression of the rubber element and the effectiveness of its sealing is far greater than could be attained in constructions in which such seal is effected by spinning or rolling a thin metal wall about a rubber liner, not to mention the simplification obtained in the elimination of such mechanical operations and the simplification in the construction of the can and of the riser in obviating the need for special fastening instrumentalities thereon.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent is:

1. The method of assembling an electrolytic condenser which consists in passing the riser through a corresponding central bore of a tapered rubber plug, inserting the riser with said plug into the can, and grasping the reduced end

of the plug with a tool and drawing it outward through the tapered bore neck of the condenser can for secure fit therein.

2. The method of assembling an electrolytic condenser which consists in passing the riser through a corresponding central bore of a tapered rubber plug, inserting the riser with said plug into the can, grasping the reduced end of the plug with a tool and drawing it outward through the tapered bore neck of the condenser can for secure fit therein, and then cutting off the excess length of protruding rubber plug.

3. The method of affixing an anode riser into the inwardly tapered neck of the can of an electrolytic condenser, which consists in axially slipping a soft rubber plug tapered to correspond with that of said neck over said riser, introducing said assembly into the can to cause the plug to seat in said neck and then pulling said plug outward through said neck, to cause the same to be tightly compressed between said neck and said riser.

4. An electrolytic condenser comprising a can, a neck to said can, an anode riser and a resilient insulating plug mounted on the lower end thereof, wherein the resilient plug is longitudinally under tension, and snugly engages the entire inner area of the neck and the encompassed surface of the riser.

5. An electrolytic condenser according to claim 4, wherein the neck has a continuous bore tapering to a minimum diameter at its free end and the plug is correspondingly tapered, whereby the plug has a wedge fit within the neck.

6. In an electrolytic condenser the combination of a can having an integral mounting neck thereon with a slightly tapered bore, an anode in said can having a riser extending axially through said neck and a flexible rubber plug having a taper corresponding to that of the bore of the neck encircling said riser wire and longitudinally under tension, and engaging the entire inner area of the neck and the encompassed surface of the riser, the upper and lower ends of said plug being substantially free from compression and flaring radially outward over the respective upper and lower ends of the neck.

DAVID JACOBS

Attendant verbal recitation is as follows: I claim a given 61 method of 62 my invention not given 63 a given 64 verbal recitation 65 and 66 a 67 the 68 right 69 words 70 not 71 disclosed 72 heretofore
